United States Patent Office

Des. 224,141
Patented July 4, 1972

224,141

LAMP

Edward Sexton, Healdsburg, Calif., assignor to The Third Eye, Inc., New York, N.Y.

Filed Feb. 25, 1971, Ser. No. 119,083

Term of patent 14 years

Int. Cl. D26—05

Cl. D48—20

FIG. 1. FIG. 2. FIG. 3. FIG. 4.

FIG. 1 is a front perspective view of a lamp, showing my new design;

FIG. 2 is a right side perspective view thereof;

FIG. 3 is a left side perspective view thereof;

FIG. 4 is a rear perspective view thereof;

FIG. 5 is a top plan view thereof;

FIG. 6 is a bottom plan view thereof.

I claim:

The ornamental design for a lamp, as shown and described.
